UNITED STATES PATENT OFFICE.

CHARLES H. BEELER, JR., OF PHILADELPHIA, PENNSYLVANIA.

DESIGN FOR A FONT OF PRINTING-TYPE.

SPECIFICATION forming part of Design No. 19,363, dated October 22, 1889.

Application filed August 29, 1889. Serial No. 322,366. Term of patent 7 years.

To all whom it may concern:

Be it known that I, CHARLES H. BEELER, Jr., a citizen of the United States, residing in the city and county of Philadelphia, State of Pennsylvania, have invented and produced a new and original Design for a Font of Type, of which the following is a specification, reference being had to the accompanying drawing, forming part thereof.

10 The leading features of my design for a font of type are the characters thereof having angular corners and shaded centers and scrolls with bulbs on the ends thereof.

I claim—

15 A design for a font of type, as shown and described.

CHARLES H. BEELER, JR.
